DESIGN FOR A PHONOGRAPH CABINET

Louis Jacobs, Stevens Point, Wis.

Application August 4, 1940, Serial No. 94,234

Term of patent 3½ years

To all whom it may concern:

Be it known that I, Louis Jacobs, a citizen of the United States and resident of Stevens Point, in the county of Portage and State of Wisconsin, have invented a new, original, and ornamental Design for a Phonograph Cabinet, of which the following is a specification, reference being had to the accompanying drawing, forming part thereof.

The figure is a perspective view of a phonograph cabinet, showing my new design.

Both sides of the cabinet are identically the same.

I claim:

The ornamental design for a phonograph cabinet, as shown and described.

LOUIS JACOBS.
